[75] Inventors: **Francis H. Arenstam**, Feeding Hills; **Mark P. LeBel**, Springfield, both of Mass.

Primary Examiner—Doris Clark
Attorney, Agent, or Firm—Robert S. Smith, Esq.

[73] Assignee: **Combustion Engineering, Inc.**, Windsor, Conn.

[57] CLAIM

[**] Term: **14 Years**

The ornamental design for refractory tile system for protection of floor tubing in chemical recovery units, as shown and described.

[21] Appl. No.: **64,383**

DESCRIPTION

[22] Filed: **Dec. 30, 1996**

FIG. 1 is a top plan view of a primary embodiment of the invention;

[51] LOC (6) Cl. **25-01**

FIG. 2 is a front view of the embodiment of FIG. 1;

[52] U.S. Cl. **D25/158; D25/138**

FIG. 3 is a side view of the embodiment of FIG. 1;

[58] Field of Search **D25/138, 156,**

FIG. 4 is a bottom view of the embodiment of FIG. 1;

D25/158, 151, 112-113; 52/602, 609, 612,

FIG. 5 is a perspective view of the embodiment of FIG. 1;

220.1, 220.4, 220.8, 220.3, 220.2, 386,

FIG. 6 is a perspective view of a second embodiment;

396.01

FIG. 7 is a perspective view of a third embodiment; and,

[56] References Cited

FIG. 8 is a perspective view of a fourth embodiment.
